WALL HUNG HOLDER FOR RECORD ALBUMS

Robert J. Pratt, 70 Le Mans Drive, Apt. 1,
Youngstown, Ohio 44512

Filed Apr. 21, 1971, Ser. No. 136,294

Term of patent 14 years

Int. Cl. D6—04

U.S. Cl. D6—130

FIG. 1

FIG. 2

FIG. 3

FIG. 4

FIG. 5

FIG. 6

FIG. 1 is a top plan view of the wall hung holder for record albums;

FIG. 2 is a front elevational view thereof;

FIG. 3 is a rear elevational view thereof;

FIG. 4 is a top elevational view of an alternate form thereof;

FIG. 5 is a front elevational view of an alternate form thereof; and

FIG. 6 is a rear elevational view of an alternate form thereof.

The sides are substantially plain.

I claim:

The ornamental design for a wall hung holder for record albums, substantially as shown and described.
